DUAL OPENING DISPLAY CARTONS

John H. Roepke, Milwaukee, Wis., assignor to David D. Davis and Gilbert F. Fitzgerald, both of Milwaukee, Wis.

Application August 6, 1957, Serial No. 676,587

8 Claims. (Cl. 229—44)

This invention relates to dual opening display cartons, and more particularly to a folding display carton having an attached cover or lid susceptible of being opened from either of its longitudinal margins for diversified display purposes.

A primary object of the present invention is to provide a dual opening display carton which can be "set up" from a one-piece blank and which has an integral cover or lid assemblage susceptible of being swung to open position from either of its longitudinal margins to vary the display of the contents of the carton, as well as to afford varying greeting or advertising displays on the inner face of the opened lid and over portions of the carton proper.

The present dual opening display carton is intended to provide an attractive and novel type of container which can be used for special occasions, as for sales events or for holiday merchandise. When the cover or lid of the carton is swung to open position along one of its longitudinal margins a certain portion of the carton and the goods therein will be visible with the remaining face of the carton covered by desired advertising indicia or pictorial or greeting representations. Reversely, when the cover or lid is opened along its other longitudinal margin the first-mentioned interior portion of the carton and its contents will be covered by a display indicia panel, exposing the other interior portions of the carton and the goods therein with the display of a different advertising or greeting panel on the inner surface of the carton lid.

A further, more specific object of the present invention is to provide a dual opening display carton which can be die cut from a one-piece blank of paperboard or the like and scored for folding to render it susceptible of being easily "set up," the latter requiring a simple stapling, gluing or fastening operation in respect to the end portion of one flap, permitting the blank as thus arranged to be shipped in a partially folded, flat, compact condition.

A further object of the invention is to provide a dual opening display carton which can be easily set up by the user and which will provide a sleeve to house and cover a rigid box insert or which can be used as a liner and cover for a preformed rigid outer box.

A further object of the invention is to provide a dual opening display carton which is of very simple construction, which is inexpensive to manufacture, which is attractive and novel in appearance and provides for varied displays of the goods therein and of greeting or advertising messages, and which is well adapted for the purposes described.

With the above and other objects in view the invention consists of the improved dual opening display carton, and its parts and combinations as set forth in the claims, and all equivalents thereof.

In the accompanying drawings, in which the same reference characters indicate the same parts in all of the views:

2

Fig. 1 is a plan view of the outstretched blank from which the improved display carton is ultimately folded and arranged;

Fig. 2 is a plan view of the dual opening display carton blank partially folded into flat form for shipment and storage;

Fig. 3 is a perspective view of the dual opening display carton with the securing panel flap disengaged to afford an exploded view of the cover or lid and showing thereadjacent a rigid box body which in use may be cased by the sleeve portion of the carton;

Fig. 4 is a perspective view of the set up display carton and inserted box body with the cover partially opened along one of its margins;

Fig. 5 is a perspective view of the complete carton and box body assemblage showing the cover lid fully opened along one margin with display indicia on one face of a panel which is raised by the lid to expose only the mid portion of the box body;

Fig. 6 is an enlarged longitudinal sectional view through the open cover of the carton of Fig. 5, said view being taken approximately along the line 6—6 of Fig. 5;

Fig. 7 is an enlarged longitudinal sectional view through the carton sleeve and encased box body taken along the line 7—7 of Fig. 5;

Fig. 8 is a perspective view of the dual opening display carton with the cover or lid opened along the margin opposite to that shown in Fig. 5;

Fig. 9 is an enlarged longitudinal sectional view taken along the line 9—9 of Fig. 8;

Fig. 10 is an enlarged longitudinal sectional view through the carton and box body taken along the line 10—10 of Fig. 8;

Fig. 11 is a longitudinal sectional view showing a modified form of the invention wherein the display carton is utilized as a liner for a rigid box body and cover; and

Fig. 12 is a cross-sectional view of the latter form of the invention.

Referring now more particularly to the drawings it will be observed from Fig. 1 that the improved dual opening display carton is folded or arranged from a one-piece blank which can be die cut, stamped or otherwise formed from paperboard or other suitable material. The blank includes a rectangular bottom forming section 15 having foldably secured to opposite longitudinal margins there-

of side wall sections 16 and 17, there being scored fold lines 18 between the inner margins of the side wall sections 16 and 17 and the bottom section 15. The outer edge of the side wall section 16 has secured thereto, by a

fold line 19, a narrow covering and display panel 20. Foldably carried by the outer end portion of the panel 20 is a securing flap 21 which, when the display carton is partially set up, is folded against and secured to the under-

surface of a cover or lid section 22. For that purpose a surface of the securing flap 21 may be gummed or it may ultimately be stapled or otherwise secured to the undersurface of the cover or lid section 22 adjacent a margin of the latter. Projecting outwardly from inter-

mediate portions of the side margins of the cover section 22 are small tabs 23 which are merely for the purpose of facilitating manual swinging of the cover section from either margin when the carton is set up. Connected by fold lines 24 to opposite end portions of the inner margin of the cover section 22 are the end portions of hinge

strips 25. The opposite ends of the hinge strips 25 are connected by fold lines 26 with the lower margin of the side wall section 16. Between the hinge strips 25 there is a rectangular opening 27 which is slightly larger than the covering and display panel 20 which is adapted to

swing through said space 27 during certain types of manipulation of the cover of the set-up display carton.

Fig. 2 illustrates one way in which the blank of Fig. 1

may have portions folded upon itself compactly for shipment and storage and from which condition the user can easily set up the carton. In the folded arrangement of Fig. 2 the bottom forming section 15 has the side wall section 16 outstretched and in the plane of the bottom 15 but the covering and display panel 20 is folded over onto the top surface of the bottom section 15. The side wall section 17 is likewise folded over onto the top surface of the bottom section 15 with the hinge strips 25 extended in the same plane over the bottom 15 and on opposite sides of the panel 20. The cover 22 is folded back over the hinge strips 25 and panel 20.

To set up the carton into its sleeve-like form the procedure illustrated in Fig. 3 is accomplished. The side wall sections 16 and 17 are extended vertically relative to the bottom section 15 and the cover or lid section 22 is raised sufficiently to expose the opening 27 between the hinge strips 25. Then the outer end portion of the covering and display panel 20 is passed through the opening 27 so as to underlie the intermediate area of the undersurface of the cover or lid section 22 and the securing flap 21 is then glued or otherwise secured to the cover or lid section 22 adjacent the margin which overlies the top edge of the side wall section 17 when the cover section is closed. After the walls and flaps and sections are folded as shown in Fig. 3 the securement of the free end of the covering and display panel 20 to the lid 22 is the only assembly operation required and with the carton thus set up in the form of the invention illustrated in Figs. 1-10 inclusive it is intended that the set-up carton form a sleeve for enclosing a relatively rigid five-sided open rectangular box or tray 28. The tray 28 is then disposed within the set up carton in the manner shown in Fig. 4 and it may be compartmental or otherwise.

The carton is especially suited for containing an assortment of merchandise and the mid-portion of the tray 28 may have disposed therein some goods or merchandise different from the goods or merchandise in the tray on opposite sides of the mid-section, with the result that the merchandise in the mid-section may be displayed as a premium or bonus. When the cover or lid section 22 is swung to open position along the hinge or fold lines 24 which connect it to the hinge strips 25, the latter will remain in horizontal position covering the sections of the tray 18 on opposite sides of the mid-section and displaying only the merchandise in the mid-section of the tray. Consequently, the then exposed faces of the hinge strips 25 may carry advertising indicia or greeting material. It will also be observed that this type of opening of the cover 22 depicted in Figs. 4 and 5 will cause the covering and display panel to swing upwardly outwardly on the hinge line 19 with the cover or lid section to which it is attached at one end, with the result that the inner face of the display panel 20 will be exposed and may carry advertising indicia or a greeting or suitable decorative material.

The reverse or alternate manner of opening the lid for the improved display carton is shown in Fig. 8. In this event the cover or lid, in opening, carries with it the hinge strips 25 so that they overlie the end portions of the inner surface of the lid section and swing on the hinge lines 26 which connect the hinge strips 25 to the side wall section 17. The covering and display panel 20, whose then forward edge is secured to the side wall section 16 by the fold line 19, is connected at its other end to the medial portion of what is then the inner edge of the lid section 22 and therefore remains in horizontal position over the medial section of the tray 28 completely covering the goods or commodity therein but exposing the goods or commodities in the end sections of the tray. The face of the covering and display panel 20 which is exposed in the condition of Fig. 8 may carry suitable advertising or greeting indicia and the same is true of the exposed inner surface portion of the lid section 22 be-

tween the hinge strips 25, which becomes exposed. Thus, as between the opening arrangements of Figs. 5 and 8 different portions of the open tray 28 are exposed and different portions are covered. In each event the coverings therefor may carry different indicia and the same is true in each event with respect to the exposed portions of the inner surface of the lid section or the panel 20. By opening the covering and display panel from either margin a unique type of display container is provided which varies the visual effect and varies the advertising and housed commodity display.

A slightly modified form of the invention is illustrated in Figs. 11 and 12, wherein the display carton elements may be directly associated with the walls of a rigid box and with its disconnected cover, in lieu of serving as a complete sleeve for a tray. The rigid five-sided box whose walls have the improved carton elements associated therewith is indicated generally by the numeral 29, and the separated rigid cover is indicated by the numeral 30. Hinge strips 25' have one pair of ends hingedly or foldably secured to a vertical side wall of the rigid box as at 31 (see Fig. 12), and the other ends of said hinge strips 25' are hingedly or foldably connected, as at 32, with an inner lining sheet 33 for the rigid cover. The numeral 20' (see Fig. 11) designates the covering and display panel which, depending upon the manner in which the lid 30 is opened, is adapted to cover either the central compartment of the box 29 or the mid section of the cover facing 33. It is, therefore, secured at one end to the cover facing adjacent one longitudinal margin of the cover, as at 34, and is secured at its other end to a side wall section of the box or liner as at 35. If the box is opened by lifting the rigid lid 30 from one margin, the hinging movement will be along the hinge connections 31 between the hinge strips 25' and the upper edge of the adjacent side wall section of the box 29 and the hinge strips will, in this mode of opening, overlie the end portions of the inner facing sheet 33 of the lid. The then exposed portions of the hinge strips may carry pictorial representations or advertising indicia, as may the exposed mid section of the cover lining sheet 33. In this form of opening the covering and display panel 20' will remain in horizontal position over the middle compartment or section of the box 29 covering the contents thereof and the then top surface of the panel 20' may carry suitable indicia.

In the alternate mode of opening the cover from the other margin, the margin of the cover will hinge during its movement upwardly on the connections 32 with the ends of the hinge strips 25' which in this event will remain in horizontal position covering the end sections of the box, but the covering and display panel 20' will hinge upwardly with and remain against the cover when it is opened and will expose the mid section of the box. If desired, the interior of the box or liner may have compartment-defining walls 36 therein, but this is merely optional.

From the foregoing description it will be seen that the present invention provides a very simple, unique and attractive dual opening display carton which is easily set up from a one-piece blank. The closure lid or cover for the carton or box can be opened from either of its longitudinal margins and each mode of opening varies the display of the contents of the carton and also gives varied forms of advertising or greeting displays on various panels and hinge strips which are differently exposed in the alternate mode of manipulating the carton lid. The improved dual opening display carton is inexpensive to manufacture, can be shipped in very flat, compact form, affords a unique type of package and display for merchandise, and is otherwise well adapted for the purposes described.

What is claimed as the invention is:

1. In a carton, first and second spaced apart upright walls defining therebetween an enclosure for articles of

merchandise, a dual opening lid for controlling access to the enclosure and having first and second spaced apart longitudinal margins adapted to substantially coincide respectively with the upper edges of the first and second spaced apart upright walls, a hinge strip traversing the upper end of the enclosure and having one end hingedly secured to the first upright wall and having its other end hingedly secured to the second longitudinal margin of the lid, and a panel also traversing the upper end of the enclosure and hingedly secured at one end to the second upright wall and hingedly secured at its other end to a portion of the first longitudinal margin of the lid.

2. In a container, first and second spaced apart walls defining therebetween an enclosure for articles of merchandise, a dual opening lid for controlling access to the outer end of the enclosure and having first and second spaced apart longitudinal margins adapted, when the lid is in closed position in a plane perpendicular to the planes of said walls, to overlie the outer edges of the first and second spaced apart container walls, a hinge strip traversing a portion of the outer end of the enclosure and having one end hingedly secured to the first wall and having its other end hingedly secured to the second longitudinal margin of the lid, and a panel spaced from the hinge strip and also traversing a portion of the outer end of the enclosure and hingedly secured at one end to the second wall and hingedly secured at its other end to a portion of the first longitudinal margin of the lid.

3. In a container, first and second spaced apart walls defining therebetween an enclosure, a dual opening lid for controlling the outer end of the enclosure and having first and second spaced apart longitudinal margins adapted, when the lid is in closed position perpendicular to the walls, to overlie the outer edges of the first and second spaced apart upright walls, a hinge strip traversing a portion of the outer end of the enclosure and having one end hingedly secured to the first wall and having its other end hingedly secured to the second longitudinal margin of the lid, and a panel also traversing another portion of the outer end of the enclosure and hingedly secured at one end to the second wall and hingedly secured at its other end to a portion of the first longitudinal margin of the lid, the lid, when hingedly opened from one margin, swinging on the hinge connection between its second longitudinal margin and the hinge strip end with the hinge strip remaining in covering relation over a portion of the enclosure and the lid carrying with it so as to cover a portion of its inner surface, the panel which hinges on its hinge connection with the second wall, the lid, when hingedly opened from its other margin, swinging on the hinge connection between the hinge strip and the first wall with said hinge strip overlying another portion of the inner surface of the lid and the panel remaining in covering relation over another portion of the enclosure.

4. In a container, first and second spaced apart parallel walls defining therebetween an enclosure, a dual opening lid for controlling the outer end of the enclosure and having first and second spaced apart longitudinal margins adapted, in the closed condition of the lid, to overlie the outer edges of the first and second spaced apart walls, a hinge strip at right angles to said walls and having one end hingedly secured to a portion of the first wall and having its other end hingedly secured to an opposed portion of the second longitudinal margin of the lid, and a panel at right angles to said walls but spaced from said hinge strip and hingedly secured at one end to a portion of the second wall and hingedly secured at its other end to an opposed portion of the first longitudinal margin of the lid.

5. In a folding carton, first and second spaced apart upright walls defining therebetween an enclosure for

articles of merchandise, a dual opening lid for controlling access to the enclosure and having first and second spaced apart longitudinal margins adapted, when the plane of the lid is perpendicular to the planes of the walls, to have its first and second margins overlie the upper edges of the first and second spaced apart upright walls, a pair of hinge strips each traversing an opposite upper end portion of the enclosure and each having one end hingedly secured to spaced apart portions of the first upright wall and each having its other end hingedly secured to the spaced apart portions of the second longitudinal margin of the lid, and a panel also traversing the upper end of the enclosure between said hinge strips and hingedly secured at one end to a portion of the second upright wall intermediate its ends and hingedly secured at its other end to a portion of the first longitudinal margin of the lid intermediate its ends.

6. A container, including first and second spaced apart parallel walls between which there is an open-faced compartment, a dual opening main lid for the entire open face of the compartment and having first and second spaced apart parallel longitudinal margins adapted to overlie the outer edges of the first and second spaced apart walls, a hinge strip traversing a portion of the outer end of the compartment and having one end hingedly secured to the first wall and having its second end hingedly secured to the second longitudinal margin of the lid and forming either a secondary lid for a portion of the open face of the compartment or a covering for a portion of the inner face of the main lid depending upon from which margin the latter is hingedly swung to open position, and a panel also traversing another portion of the outer end of the compartment and hingedly secured at one end to the second wall and hingedly secured at its other end to a portion of the first longitudinal margin of the main lid, said panel forming a secondary lid for another portion of the open face of the compartment or a covering for another portion of the inner face of the main lid depending upon from which margin the latter is hingedly swung to open position.

7. In a folding container set-up from a one-piece blank, a bottom section, first and second longitudinal walls hingedly connected to opposite margins of the bottom section, a dual opening lid having first and second spaced apart longitudinal margins, a hinge strip having one end foldably secured to a portion of the first wall and having its other end foldably secured to a portion of the second longitudinal margin of the lid, and a panel spaced from the hinge strip and foldably secured at one end to the second wall and foldably secured at its other end to a portion of the first longitudinal margin of the lid.

8. In a container, first and second spaced apart walls defining therebetween an enclosure, a dual opening lid for controlling the outer end of the enclosure and having first and second spaced apart longitudinal margins adapted, when the lid is in closed position perpendicular to the walls, to overlie the outer edges of the first and second spaced apart upright walls, a hinge strip traversing a portion of the outer end of the enclosure and having one end hingedly secured to the first wall and having its other end hingedly secured to the second longitudinal margin of the lid, both surfaces of the hinge strip bearing display indicia, and a panel also traversing another portion of the outer end of the enclosure and hingedly secured at one end to the second wall and hingedly secured at its other end to a portion of the first longitudinal margin of the lid, both surfaces of the panel bearing display indicia, the lid, when hingedly opened from one margin, swinging on the hinge connection between its second longitudinal margin and the hinge strip end with the hinge strip remaining in covering relation over a portion of the enclosure and exposing the display indicia on its outer face and the lid carrying with it so as to cover

75 a portion of its inner surface, the panel which hinges on

its hinge connection with the second wall and exposing the display indicia on the under face of the panel, the lid, when hingedly opened from its other margin, swinging on the hinge connection between the hinge strip and the first wall with said hinge strip overlying another portion of

the inner surface of the lid and exposing the display indicia on its under face and the panel remaining in covering relation over another portion of the enclosure and exposing the display indicia on its outer face.
